US00D954864S

(12) **United States Design Patent** (10) **Patent No.:** **US D954,864 S**
Carmichael et al. (45) **Date of Patent:** **** Jun. 14, 2022**

(54) **CARRIAGE FOR EXERCISE RACK**

- (71) Applicant: **Coulter Ventures, LLC.**, Columbus, OH (US)
- (72) Inventors: **James Carmichael**, Hilliard, OH (US); **Ahmik Jones**, Upper Arlington, OH (US); **Bill Henniger**, Columbus, OH (US)
- (73) Assignee: **Coulter Ventures, LLC.**, Columbus, OH (US)
- (**) Term: **15 Years**
- (21) Appl. No.: **29/741,487**
- (22) Filed: **Jul. 13, 2020**

Related U.S. Application Data

(57) **CLAIM**

The ornamental design for a carriage for exercise rack, as shown and described.

DESCRIPTION

FIG. 1 is a top, front, left perspective view of a carriage for exercise rack showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a bottom, front, right perspective view thereof; and,
FIG. 9 is a top, front, left perspective view thereof shown in a condition of use.

The broken lines in FIGS. 1-8 show portions of the carriage for exercise rack which forms no part of the claimed design. The additional broken lines shown in FIG. 9 are to show environment structure and form no part of the claimed design.

1 Claim, 6 Drawing Sheets
